(57) **CLAIM**

The ornamental design for a table lamp, as shown and described.

DESCRIPTION

FIG. 1 is a front, left, top perspective view of a table lamp, showing my new design;

FIG. 2 is a rear, right, bottom perspective view thereof;

FIG. 3 is a front, left, top elevational view of the table lamp in another angle;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 2;

FIG. 11 is a front, left, top perspective view of the table lamp in a detached state;

FIG. 12 is a rear, right, bottom perspective view of the table lamp in a detached state; and,

FIG. 13 is an enlarged view of detail 13 in FIG. 12.

The dashed broken lines in the figures are for the purposes of illustrating portions of the table lamp and form no part of the claimed design.

The dash-dot-dash broken lines are for notating enlarged views and form no part of the claimed design.
